ASSEMBLING MACHINE

John T. Lancaster, Newton, Mass., assignor to
 United Shoe Machinery Corporation, Borough
 of Flemington, N. J., a corporation of New
 Jersey

Application November 30, 1939, Serial No. 306,776

62 Claims. (CL 12—4)

This invention relates to machines for use in the manufacture of shoes and is illustrated herein as embodied in a machine for assembling shoe parts upon lasts.

It is customary in assembling lined uppers and molded counters to first apply an adhesive to the counter and then insert the counter manually between the upper and the lining. The operator presses the lining against the inserted counter and a last is then inserted. The proper positioning of the counter in the upper is dependent upon the skill of the operator and if the rear portion of the counter is not properly aligned with the back seam of the upper this condition will exist during the lasting of the shoe and the resulting shoe will not have the desired appearance. It is an object of the present invention to provide mechanism for inserting a counter in a lined upper in such a manner that this difficulty is overcome. In accordance with the illustrated embodiment of the invention, means are provided for supporting a lined upper for the reception of a counter and means are also provided for supporting a counter. After the counter and upper have been properly placed in their respective supporting means, mechanism under the control of the operator moves the counter supporting means to move the counter into the upper in a predetermined position with respect thereto. The upper is supported in a vertical position with the forepart extending downwardly which facilitates the placing of the upper on its support, the heel part thereof being supported by grippers engaging the top margin and the lasting margin thereof. The counter support when positioned to receive a counter is out of alignment with respect to the upper so as not to obstruct the placing of the upper on its supporting means by the operator.

In order to facilitate the insertion of the counter in the upper the lining should be moved inwardly with respect to the upper, and mechanism for performing this function forms another feature of the present invention. To this end the illustrated machine includes a gripper for gripping the lining at the lower portion thereof and mechanism for moving the lining gripper in timed relation with the movement of the counter inserting means to move the lining inwardly away from the upper and then back into engagement with the inserted counter. Following this movement of the lining gripper, one of the jaws thereof is moved out of engagement with the lining and the gripper is then moved outwardly away from the upper leaving the lining

in engagement with the inserted counter. The lining gripper moves about an axis extending substantially through the line of stitching of the lining to the upper at the rear part thereof when the upper is supported in the machine so that the lining during its movement is maintained free from wrinkles and the movement of the lining gripper about this axis forms another feature of the present invention.

10 A further object of the present invention is to provide mechanism for inserting a last or form into the upper with a rocking motion of such a character that an effective wiping action of the lining at the rear part of the upper takes place, the last being inserted following the insertion of the counter. In the illustrated machine, a last support is positioned rearwardly of the vertically supported upper and is arranged to receive a last passed through the bottom opening of the upper and secured thereto by clamping members which centralize the last with respect to the supported upper. When so supported, the forepart of the last extends outwardly through the bottom opening of the upper and the heel part extends through the top opening of the upper. The last support is then moved vertically until the heel end of the last engages the gripper for the top margin of the upper, this gripper acting as a gage to insure the proper vertical positioning of the last support. The last support is then rocked about an axis extending substantially through the last adjacent to the hinge thereof to move the heel end thereof toward the lower edge of the upper and at the same time a lengthwise tension is applied to the upper so that the heel end of the last exerts a strong wiping action on the lining.

In accordance with a further feature of the invention the counter supporting grippers are arranged to exert a wiping action upon the lining of the upper after the insertion of the last. As illustrated, the inner jaws of these grippers are moved inwardly with respect to the flange of the counter after the last has been inserted in the upper and the outer faces of these jaws engage the lower margin of the lining and during the inward movement of the jaws they tend to pull the lining tightly about the last. During this inward movement of the inner jaws, the outer jaws are arranged to exert a pressure against the counter to move the counter toward the last. After the inner jaws have moved out of engagement with the flange of the counter the outer jaws then move away from the flange and the counter-inserting mechanism

is then moved back to the loading position. During the movement of the counter-supporting grippers away from the flange of the counter the lasting margin of the upper is pulled tightly over the heel seat of the last and the upper is then tacked to the heel end of the last at a point adjacent the back seam and the upper margin thereof. Mechanism is also provided for inserting a tack through the lasting margin of the upper at the rear, through the flange of the counter, the lining and the heel seat of the inner sole which is attached to the bottom of the last. The arrangement of this tacking mechanism forms another feature of the present invention. The upper, counter and last are now assembled and are ready for the pulling-over and lasting operations.

The above and other features of the invention will now be more particularly described by reference to the accompanying drawings and thereafter pointed out in the appended claims.

In the drawings,

Fig. 1 is a front elevation of a machine embodying the features of the present invention;

Fig. 2 is a right side elevation of the machine;

Fig. 19 is a view taken at right angles to Fig. 18 and showing the side and rear grippers for the counter;

Figs. 20 to 23 are views showing the side grippers for the counter in various positions;

Fig. 24 is a view taken on the line XXIV—XXIV of Fig. 19;

Fig. 25 is a view taken on the line XXV—XXV of Fig. 23;

Fig. 26 is a detail side elevation of the last supporting mechanism with certain parts shown in cross section;

Fig. 27 is a top view of the last supporting mechanism;

Fig. 28 is a front elevation of the clamping members associated with the last supporting assembly;

Fig. 29 is a view of the operating cam for the last inserting mechanism;

Fig. 30 is a view of the operating cam for the lining gripper release mechanism taken on the line XXX—XXX of Fig. 3; and

Fig. 31 is a chart illustrating the various cam motions.

As shown in Figs. 1 to 4, the frame of the machine comprises a base 10, side walls 12 and 14, and horizontal walls 16 and 18 located adjacent to the upper part of the machine, these horizontal walls connecting the side walls 12 and 14. A wall 19 connects the lower portions of the walls 12 and 14. The horizontal wall 16 is provided with a pair of bosses 21 and 23 for supporting shafts 22 and 24, respectively. The shafts 22 and 24 are held against movement in the respective bosses by means of the set screws 26 (Fig. 6).

Referring to Figs. 6 and 7, gib 28 are secured to the lower sides of the bosses 21 and 23 and form therewith and with the wall 16 a guideway for a slide 30. The rear lower part of the slide 30 is provided with rack teeth 32 which mesh with a gear 34 fastened to a shaft 36. The shaft 36 is carried by means of bearings 38 and 40 (Fig. 1) in the side walls 12 and 14 respectively. A bearing 41 (Fig. 6) connected to the boss 23 supports the shaft intermediate its ends. A hand wheel 42 (Figs. 1 to 3) is mounted on the right end of the shaft 36 and forms means whereby the operator may turn the shaft 36 and with it the pinion 34 to adjust the slide 30 longitudinally with respect to the shafts 22 and 24. A spring 44 (Fig. 1), secured to the wall 12 of the machine, has a free end bearing against the hub of the hand wheel 42 to form a frictional brake for preventing unintentional rotation of the shaft 36.

The slide 30 has a downwardly extending portion at the forward end thereof, as shown in Fig. 7, and is provided with a hole 50 for receiving the shank portion 52 of a gripper jaw 54. A set screw 56 threaded into the slide holds the shank 52 rigidly in place so that the gripper jaw 54 is maintained rigid with respect thereto. This gripper jaw 54 is designed to engage the inner side of the top margin of the heel portion of the upper, and the lower part of the shank portion 52 forms a gage by means of which the distance of the top margin of the upper from the front of the machine may be predetermined.

Slidably mounted on the shank portion 52 of the gripper jaw 54 is a block 58 carrying a gripper jaw 60 which cooperates with the gripper jaw 54 to hold the rear part of the upper at the top margin. The block 58 is urged downwardly by a spring 62 acting between the block 58 and the slide 30. The block 58 is provided with a notch 64 in a portion thereof extended to one side of the gripper jaw 60, as shown in Fig. 6, and a latch 66 co-operates with this notch to hold the block 58 in its upper position, as illustrated in

Figs. 6 and 7. The latch 66 is pinned to a shaft 70 journaled in the slide member 30 and a handle 72 extending forwardly of the machine is pinned to the shaft 70 at the opposite side of the slide. The latch 66 has a projection 74 at the upper end thereof against which a spring 76 seated in a recess in the slide 30 acts. This spring urges the latch 66 in a clockwise direction, as viewed in Fig. 7, to maintain the lower end thereof in engagement with the notch 64 of the block 58. The spring 76, however, permits movement of the latch in a counterclockwise direction to release the block 58 when the handle 72 is moved downwardly by the operator. Upon release of the latch by the operator the spring 62 forces the block 58 downwardly so that the gripper jaw 60 will move firmly into engagement with an upper which has been placed on top of the gripper jaw 54.

The slide 30 and the block 58 are provided with aligned vertical bores 80 and 82 for slidably supporting a tack driver 84. The upper end of the tack driver is forked at 86 and a pin 88 extends through the forked portion. The pin 88 is mounted in spaced lugs 90 carried by an operating lever 92 which is operated in a manner to be described. The slide 30 and the block 58 are also provided with aligned tack delivering passageways 94 and 96, these passageways being connected by means of a tube 98 to a suitable tack delivering apparatus (not illustrated). The passageway 96 in the block 58 terminates at the bore 82 through which the tack driver 84 extends and when the block 58 is in its retracted position, as illustrated, the lower portion of the tack driver closes the lower end of the passageway 96, thus preventing delivery of tacks from the passageway 96 to the bore 82. When the operator releases the latch 66, thus permitting downward movement of the block 58, the block moves downwardly with respect to the tack driver 82 and the lower end of the passageway 96 moves below the lower end of the tack driver 84. The tack which has been delivered to the passageway 96 will now move into the bore 82 below the tack driver and may be retained in this position by means of springs 102 attached to each side of the block 58 until the tack driver is actuated. The lower ends of the springs converge and form a resilient stop for preventing accidental movement of the tacks therefrom, but will yield to permit movement of tacks therebetween upon actuation of the tack driver.

The tack driver operating lever 92 has an enlarged bearing portion 110 (Figs. 3 and 6) intermediate the ends thereof and the lever is journaled by means of this bearing on a shaft 112. The shaft 112 is mounted in bearings 114 and 116 mounted in the side walls 12 and 14 of the frame of the machine, respectively. The rear end of the lever 92 has connected thereto a cam follower 120 (Figs. 3 and 14). This cam follower rides in a cam slot 122 of the cam 124, as shown by the dotted lines in Fig. 14. The cam 124 is keyed to a shaft 126, driven in a manner to be later described. The shaft 126 and the cam 124 rotate in a clockwise direction, as viewed in Fig. 14, and at the proper time in the cycle the lever 92 will be rocked about the shaft 112 in a direction to move the forward end of the lever downwardly which will, in turn, move the tack driver 84 downwardly to drive a tack into the last through the rear part of the upper adjacent to the back seam. The delivery end of the tack driver assembly is positioned to one side of the 75

center line of the jaws 54 and 60, so that the tack will not be delivered through the back seam of the upper, if the upper is properly positioned with the back seam in the plane of the center line of the jaws.

Journaled on a shaft 130 (Figs. 3, 6, 7 and 13) and extending toward the front of the machine is a gripper releasing and latch setting lever 132 having an enlarged cylindrical portion 134 intermediate the shaft 130 and the forward end thereof. This enlarged portion 134 is located below the lateral extension 136 of the block 58 which carries the gripper jaw 60 and this enlarged cylindrical portion of the lever is arranged to act against the block and move the block upwardly against the force of the spring 62 upon movement of the lever 132 upwardly. The lever 132 extends rearwardly from the shaft 130 and at its inner end carries a cam follower 137 (Figs. 3 and 13) which rides in the cam groove 138 cut in the side of a cam 140. This cam groove is illustrated in dotted lines in Fig. 13. The cam 140 is keyed to the driven shaft 126 so that the cam 140 and the cam 124, previously described, rotate together. The cam 140 is arranged to move the lever 132 in a clockwise direction (Fig. 13) so as to lift the upper jaw 60 away from the jaw 54 subsequent to the tacking operation. The block 58 carrying the gripper jaw 60 will be moved upwardly by the lever 132 until the latch 66 engages the notch 64 of the block 58 to hold the block in its retracted position against the force of the spring 62.

Pinned to the forward ends of the shafts 22 and 24 is a supporting and guiding member 150 (Figs. 8-10) for the grippers which engage the lasting margin of the heel end of the upper. The member 150 is provided with a vertically extending recess in the central portion thereof the shape of which is shown in Fig. 10. As seen in this figure the ends of the recess are cut deeper in the member 150 than is the central portion thereof. Slidably mounted in the deeper portions of the recess are the shank portions 152 of the gripper jaws 154. These shank portions are connected together at their upper ends by means of a bar 156 and to the central portion of this bar is connected the upper end of an L-shaped member 158 the lower end of which extends outwardly from the supporting member 150, as indicated in Fig. 8. The outer end of the member 158 is notched at 160 and a pivoted latch member 162 co-operates with the notched portion of the L-shaped member 158 to maintain the member 158 in the position illustrated in Fig. 8. Since the shank portions 152 of the gripper jaws 154 are connected to the L-shaped member 158 by means of the bar 156, these gripper jaws will also be maintained in the vertical position illustrated, by the latch 162. This latch is pivoted by means of the pivot screw 164 to the side of the supporting member 150 and is held in engagement with the notch 160 by means of the leaf spring 166 bearing against the outer surface of the latch, this spring being secured to the supporting member 150 by means of a screw 168. Extending toward the front of the machine is a handle 170 the inner end of which is secured to the latch 162 or the handle may be formed integrally with the latch. By pressing downwardly on the handle 170, the latch 162 will be retracted from the notch 160 of the L-shaped member 158, thus permitting downward movement of this member and the gripper members 154. A spring 171 has one end in engagement with the bar 156

and the other end in engagement with a pin 172 extending through a slide 178 and this spring removes the gripper members downwardly with respect to the slide upon release of the latch 162.

Inner gripper jaws 176 co-operate with the gripper jaws 154 to grip the lasting margin of the upper at the heel end thereof. The gripper jaws 176 are secured to the lower end of the slide 178 which slides in the outer part of the recessed portion of the supporting member 150, or that portion toward the front of the machine. Gibs 180 (Fig. 10) are secured to the forward wall of the member 150 and co-operate with the recess to form a guideway for the slide 178. The upper portion of the slide 178 is forked, as at 182, (Fig. 8) and receives the end of an arm 184 between the forked portions thereof. A pin 186 extending through the forked portion of the slide and through the end of the arm 184 pivotally secures these members together. The other end of the arm 184 is telescopically received by the forward end of the arm 92. This permits adjustment of the gripper assembly including the gripper jaws 60 and 54 with respect to the gripper jaws 154 and 176 heightwise of the upper.

Mounted adjacent the gripper jaws 154 and between the shank portions 152 thereof is a wiper 190 (Fig. 9). This wiper is secured to the slide 178 by means of a spring pressed plunger 192 engaging a recess in the rear of the wiper. The sides of the wiper are cut away to embrace the shank portions 152 of the gripper jaws 154. The side of the wiper 190 toward the front of the machine is flanged, as at 200, and these flanges co-operate with the spring pressed plunger 192 to maintain the wiper in place.

The body of the wiper member 190 is provided with a vertical passageway 202 which is in alignment with a passageway 204 in the supporting member 150, the upper end of this passageway being connected to a tube 206 which is in turn connected to a tack delivery mechanism. The lower end of the passageway 202 terminates in a passageway 208 extending horizontally through the wiper member and located below the delivery end of the vertical passageway 202 is a tack positioning device 210 pivoted at 212 to the body of the wiper member. When the member 210 is in the position illustrated, the tack, which is delivered from the passageway 202, will lie on the surface of the member 210, as illustrated in Fig. 9, in which position it is inclined downwardly and forwardly with respect to the passageway 208. When the member 210 is turned in a counterclockwise direction, however, it will move the tack into a horizontal position in the passageway 208 whereupon it can be delivered therefrom through the surface of the wiper member 190. The member 210 has a tooth at the rear portion thereof which engages a recess in a pivoted member 214. The member 214 is biased in a counterclockwise direction by means of a leaf spring 216 to a position in which a portion of the member extends into the passageway 208. A tack driver 220 is slidably mounted in the passageway 208 and has a cut-out portion adjacent to its forward end which permits movement of the member 214 to the position illustrated. As the tack driver 220 is moved toward the right (as viewed in Fig. 9) in order to drive a tack, it will cause the member 214 to rotate in a clockwise direction until no portion thereof lies in the passageway 208, and this movement of the member 214 causes the tack positioning device 210 to move in a counterclockwise direction to move the tack supported thereby into a horizontal position

in the passageway 208 and in alignment with the tack driver 220 so that the tack will be driven through the overlasted portion of the upper, the counter flange, the lining and the innersole attached to the last which has been inserted in the upper.

The tack driver 220 is pivotally connected to an operating lever 222 which is in turn pivoted at 224 to a bracket 226. This bracket is secured by means of screws 228 to the upper end of the slide member 178 and the lower end of the bracket is spaced from the slide member. The upper end of the lever 222 extends forwardly of the machine and is pivoted to a rod 230 the upper end of which extends through an aperture in a forwardly projecting part 232 of the bracket 226. A spring 234 engages a pin 236 in the lower end of the rod 230 and the other end of this spring bears against the under side of the projecting portion 232 of the bracket. This spring acts to urge the lever 222 in a counterclockwise direction to move the tack driver 220 to the right, as viewed in Fig. 9, to drive a tack. With the parts in the positions illustrated in Fig. 9, the lever 222 is prevented from moving about its pivot. For this purpose the lever 222 carries a projection 240 which engages a latch member 242 pivoted at 244 to the slide 178. The latch 242 is biased into latching position by means of the spring 246 one end of which is seated in a recess in the slide 178 and the other end of which bears against the rear part of the latch. A pin 248 extends laterally from the latch 242 and is arranged to engage a pin 250 mounted in the lower part of the fixed supporting member 150 upon downward movement of the slide to a predetermined position. As the slide moves downwardly and the projecting pin 248 on the latch 242 engages the pin 250 the latch will be moved against the force of the spring 246 and the forward end thereof will move out of engagement with the projection 240 of the operating lever 222. The lever 222 is now free to move under the influence of the spring 234 to operate the tack driver 220.

As the lever 92 is operated by the cam 124 to operate the tack driver 84 of Fig. 7 it will simultaneously cause a downward movement of the slide 178. This will take place after the lasting margin of the heel portion of the upper has been gripped by the grippers 154 and 176 and after the last has been inserted in the upper. These grippers will now move down as a unit with the slide 150 and will pull the upper tight over the last and the wiper 190 will wipe the upper over the heel portion of the last. As the grippers and wiper reach the lowermost position the latch 242 will be released by engagement with the pin 250 so that the lever 222 will move under the influence of the spring 234 and the tack driver 220 will move to the right, thus positioning the tack supported on the positioning member 210 horizontally in the passageway 208 and driving the tack through the margin of the upper, the lining, the flange of the counter, which also will be inserted at this time by means to be described, and the innersole attached to the last.

The forward end of the arm 132 (Fig. 13) terminates in an enlarged cylindrical portion 260 which underlies the projecting portion of the L-shaped member 158, as shown in Fig. 8. As the forward end of the arm 132 is moved upwardly by the cam 140, the cylindrical portion 260 thereof will engage the projecting portion of the member 158 to move the gripper jaws 154 upwardly simultaneously with the engagement of

the portion 134 of the arm with the projecting portion 136 of the block 64 carrying the gripper jaws 60 of Figs. 6 and 7. Thus, the movement of the arm 132 will cause simultaneous upward movement of the grippers 60 and 154 to release the rear part of the upper.

While the gripper jaws are being moved upwardly by the arm 132, the arm 92 (Fig. 9) also moves upwardly to raise the slide 178 carrying the gripper jaws 176. This movement of the slide 178 is slower than the movement of the gripper jaws 154 so that the gripper jaws 154 will move upwardly with respect to the gripper jaws 176 to open the gripper. The tack driving lever 222 has a shoulder 262 adjacent to the pivot 224 thereof, and this shoulder is arranged to engage a bar 264 extending across the upper forward part of the fixed supporting member 150. Accordingly, as the slide moves upwardly carrying with it the lever 222, the shoulder 262 thereof will engage the bar 264 which will cause clockwise rotation of the lever 222 against the force of the spring 234 until the projection 240 moves into latching engagement with the latch 242. This movement of the lever 222 causes movement of the tack driver 220 back to the position illustrated in Fig. 9, which, in turn, causes movement of the tack positioning device 210 to the position illustrated for receiving a tack delivered thereto through the passageway 202.

The forepart gripper is shown in Figs. 1, 2, 4, and 11 and comprises a relatively fixed outer gripper jaw 270 and a relatively movable co-operating gripper jaw 272. These gripper jaws are carried by a support 274, the outer jaw 270 being fixedly carried thereby and the gripper jaw 272 being pivoted to the support 274 at 276. The movable gripper jaw 272 is in the form of a bell-crank lever, one end of which terminates in the gripping surface and the other end of which is connected by means of links 278 (Fig. 4) to a rod 280 which is in turn pivoted to a handle 282 pivoted to the lower part of the supporting member 274 at 284. The rod 280 extends through a bracket or guiding member 286 fixed to the forward wall of the supporting member 274, and a spring 288 surrounding the rod 280 has one end in engagement with the upper end of the bracket 286 and the other end in engagement with the upper end of the rod 280. The rod 280 is thereby urged upwardly by the spring, whereby the gripper jaw 272 is moved toward the gripper jaw 270 to hold the toe end of an upper therebetween. In inserting an upper between the gripper jaws, the handle 282 is moved downwardly to move the rod 280 against the force of the spring 288, which causes the jaw 272 to move away from the jaw 270.

The support 274 is slidably mounted on a block 290 for lateral adjustment, the support embracing three sides of the block as shown in Fig. 4, and gibbs 275 connected to the top and bottom of the support embrace the back of the block 290. This block is provided with a pair of recesses 292 and 294 (Fig. 5) for selectively receiving a spring pressed plunger 296 carried by the support 274. This plunger is connected to a handle 298 and is urged toward the block by means of a spring 300. With this arrangement, the support 274 may be fixed in either of two positions for the purpose of accommodating an upper for either a right or a left shoe. With the support in the position shown in Fig. 5, the gripper is positioned to receive the forepart of an upper for a left shoe, and if the support

is adjusted to the left, the gripper will be positioned to receive an upper for a right shoe.

The supporting block 290 is pinned to a shaft 302 (Fig. 4) which is in turn keyed to a split bearing 304. A screw 306 passes through the split portion of the bearing so that the shaft 302 may be fixed in any desired axial position with respect to the bearing. The bearing 304 is carried by an arm 314 fixed to a shaft 310 supported in bearings 312 in the side walls of the frame of the machine. An arm 314 fixed to the shaft 310 is forked at its upper end and receives between the forked portions thereof a threaded rod 316. Adjusting nuts 318 (Fig. 13) are provided for adjusting the position of the rod 316 with respect to the arm 314, and a spring 322 acting between nuts 320 and a washer 324 urges the rod 316 toward the right with respect to the arm 314. The inner end of the rod 316 is pivoted to a lever 324 fulcrumed on a shaft 326 supported by a bearing 327 in the side wall 12 of the machine. The upper end of the lever 324 has connected thereto a cam follower 330 which is received by a cam groove 332 in the right side of the cam 140, as illustrated in Figs. 3 and 4.

Simultaneously with the movement of a last into the upper, by mechanism to be described, the lever 324 is moved by the cam 140 in a clockwise direction which will in turn cause movement of the shaft 310 in a counterclockwise direction. Since the forepart gripper jaws 270 and 272 are carried by the arm 308 extending downwardly from this shaft, this movement of the shaft will cause a downward movement of the forepart gripper to exert a lengthwise tension on the upper, the rear part of which is held by the rear part grippers heretofore described so that, as a last is inserted into the upper, a wiping action upon the lining of the upper will take place. The spring 322 provides a yielding connection between the lever 324 operated by the cam 140 and the shaft 310 so that the upper is subjected to a yielding lengthwise pull.

Provision is made for moving the lining away from the heel portion of the upper to facilitate insertion of a counter therein and to move the lining back into place following the insertion of a counter, as shown in Figs. 1, 3, 11, and 12. A lining gripper jaw 350 (Fig. 11) is carried by an arm 352 and a co-operating gripper jaw 354 is pivoted at 356 to the arm 352. The inner end of the arm 352 is formed with a shoulder portion 360. A rod 362 is pivoted to the gripper jaw 354 and 364 and the other end of the rod passes through an aperture in the portion 360 of the arm 352. A spring 366 between the shoulder portion 360 of the arm and the gripper jaw 354 urges the gripper jaw 354 toward the gripper jaw 350 to hold the lower edge of a lining therebetween. A handle 368 on the jaw 354 extends toward the front of the machine and enables the operator to move the gripper jaw 354 away from the gripper jaw 350 for the purpose of inserting the lower portion of the lining in the gripper.

The arm 352 at the end opposite the gripper jaw 350 is rigidly connected to an arm 370 by means of a rod 372 (Figs. 1 and 11). The arm 370 is laterally disposed, as indicated in Fig. 1, with respect to the various grippers for the upper so that the arm 352 may be swung about a shaft 374 (Fig. 12) without interfering with the upper. The arm 370 is rotatably mounted on the shaft 374 which is in turn connected to the side wall 12 of the frame of the machine by means of the boss 376 and the screw 378 (Fig. 1). The axis of this shaft extends substantially

through the point of stitching between the lining and the upper at the heel end thereof so that after the lining has been gripped by the jaws 350 and 354 and these jaws then moved about the axis of the shaft 374, the lining will move about the line of stitching as a center so that it will not wrinkle or be subjected to a stretching action during its movement. Rotatably carried by the shaft 374 and fixed to the arm 370 is a pinion 380 which is in engagement with a gear segment 382 carried by the end of a lever 384 (Fig. 12). The lever 384 is fulcrumed on the shaft 130 and the opposite end of the lever carries a cam follower 388. This cam follower is mounted in the cam groove 390 of a cam 392 keyed to the driven shaft 126. As the shaft 126 rotates in a counterclockwise direction from the position shown in Fig. 12, the lever 384 will first move in a clockwise direction, rotating the gear 380 in a counterclockwise direction, thereby moving the lining gripper through substantially 135° or to the intermediate position shown in Fig. 12. Upon continued rotation of the cam 392 the lining gripper will be moved back to the position illustrated in full lines in Fig. 12 and upon still further rotation of the cam the gripper will move through substantially 180° to the upper broken line position. Before moving outwardly from the upper this second time, however, the gripper jaw 354 is moved away from the gripper jaw 350 to release its hold on the lining, since at this time the counter will have been inserted between the lining and upper by means to be described and this last movement of the lining gripper through 180° is to get it out of the way to permit the insertion of a last within the upper.

For the purpose of opening the lining gripper, a release member 396 (Figs. 1 and 30) is mounted on arm 398 rotatable on the shaft 374. A pinion 400 is rotatably mounted on the shaft 374 and fixed to the arm 398. The pinion 400 engages a gear segment 402 formed at the end of a lever 404 pivoted on the shaft 130. The opposite end of the lever 404 carries a cam follower 406 which engages the cam groove 408 in the cam 392. The cam groove 408 is so designed that no movement will be imparted to the lever 404 until the lining gripper has moved the lining outwardly from the upper and has started to move the lining back. At this time the release member 396 starts to move in a counterclockwise direction (Fig. 30) from the full-line position to the broken line position. The lower end of the rod 362 (Fig. 11) carries a laterally projecting pin 410 which is in the path of movement of the release member 396 when the lining gripper is in the full-line position of Fig. 12. The member 396 is arranged to engage the pin 410 and to move the rod 362 against the force of spring 364 after the lining gripper has returned the lining to the proper position against the previously inserted counter. This downward movement of the rod 362 causes the gripper jaw 354 to move away from the gripper jaw 350 to release the hold upon the lower margin of the lining so that the lining gripper may move outwardly from the upper without disturbing the position of the lining.

Mechanism for supporting and inserting a counter in the upper will now be described. The counter supporting mechanism, indicated generally by the reference character 420 (Figs. 2, 3 and 14) is mounted on a bracket 422 fastened to a shaft 424. The shaft 424 extends from front

to rear of the machine and is slidably and rotatably supported in bearings 426 and 428 (Figs. 3 and 14). The rear part of the shaft 424 has longitudinally extending teeth 430 cut in the lower surface thereof and these teeth are in engagement with the rack teeth 432 formed in the end of a shaft 434 extending across the rear part of the frame of the machine and slidably mounted in bearings 436 and 438 in the walls 12 and 14 of the machine, as shown in Fig. 3. The shaft 434 carries a cam follower 440 (Figs. 14 and 16) which is received by the cam groove 442 formed in the periphery of the cam 124. The cam groove 442 is so formed that as the cam 124 rotates in a clockwise direction, as viewed in Fig. 14, the supporting bracket 422 for the counter supporting mechanism 420 will be swung from the vertical position illustrated in Fig. 1 to a position in which the counter is somewhat below the rear portion of the upper and, upon further rotation of the cam, the bracket 422 will be swung slightly in the reverse direction to bring the counter supported thereby into alignment with the rear portion of the upper.

Mounted on the shaft 424 intermediate the ends thereof is a member 450 provided in the lower surface thereof with the rack teeth 452. Rotation of the member 450 with the shaft 424 is prevented by the engagement of the inner flat side thereof with the outer surface of the side wall 14 of the frame of the machine as shown in Fig. 15. While the shaft 424 is rotatable with respect to the member 450, axial movement thereof with respect to this member is prevented by means of keys 454 which are held in grooves cut in the top surface of the member 450 by means of the screws 456. Each of the keys 454 has a tooth in the bottom thereof which engages a peripheral groove 458 cut in the surface of the shaft 424. Accordingly, any axial movement of the member 450 will be imparted to the shaft 424 by means of the keys 454 which hold the shaft and the member 450 against relative movement axially of the shaft.

Carried by a shaft 460 mounted in wall 14 of the frame of the machine (Figs. 14 and 15) is a gear 462 meshing with the rack teeth 452 and a second gear 464 which may be formed integral with the gear 462 meshes with a gear segment 466. This gear segment is carried by the lower end of an arm 468 keyed to the shaft 112 to which is also keyed an arm 470 carrying at the lower end thereof a cam follower 472 which engages a cam slot 474 cut in the left side of the cam 124. As the cam 124 rotates in a clockwise direction the bracket 422 carrying the counter supporting mechanism 420 is swung from a vertical to a horizontal position by the mechanism previously described, and the arm 468 carrying the gear segment 466 is moved in a clockwise direction, thus moving the gears 464 and 462 in a counterclockwise direction. This movement of the gear 462 causes movement of the rack 452 and, accordingly, of the shaft 424 toward the left, as viewed in Fig. 14, thus moving the counter supporting mechanism 420 toward the machine. The axial and rotational movements of the shaft 424 are so correlated that the shaft 424 moves the counter supporting mechanism inwardly as

it is being moved downwardly and the counter carried by the supporting mechanism 420 enters the upper when the supporting bracket 422 is in its lowermost position. During the last portion of the inward movement of the counter into the upper the bracket 422 is moving in the reverse

direction or upwardly so that the counter is moved into engagement with the rear portion of the upper. When the movements of the shaft 424 have terminated the counter will be in the desired position between the lining and the upper.

Referring to Figs. 17 to 25, it will be seen that the counter supporting mechanism 420 comprises three grippers for supporting the flange of the counter at the rear and the sides thereof. Rotatably supported in the end of the bracket 422 remote from the shaft 424 are shafts 480 and 482. These shafts carry arms 484 and 486 (Fig. 20), the arms having portions adjacent the shafts extending toward each other and having teeth 490 and 492 forming a connection between the arms whereby movement of one arm will impart equal and opposite movement to the other. The tooth 492 on the arm 486 is extended laterally at 494 (Figs. 17 and 19), and this tooth meshes with teeth 496 on the upper portion of an arm 498 (Fig. 19). The arm 498 is supported on a shaft 500 located at right angles to the shafts 480 and 482. The ends of the arms 484, 486, 498 remote from the supporting shafts pivotally carry inner gripper jaws 502 arranged to engage the inner side of the flange of a counter. Arms 506, 508 and 510 are connected to the arms 484, 486 and 498, respectively, by means of links 512. These latter arms are urged toward the outer ends of the arms 484, 486, 498 by means of springs 514 interposed between the upper ends of the arms 506, 508 and 510 and the adjacent portions of the arms 484, 486 and 498. These arms are also urged inwardly toward the arms 484, 486 and 498 by means of the springs 515. Set screws 516 carried by the outer arms limit the movement thereof toward the inner arms under the influence of the springs 515. Gripper jaws 518 are yieldingly carried by the lower ends of the outer arms by means of leaf springs 520 and the jaws 518 co-operate with the jaws 502 to support the counter with the flange thereof between the co-operating jaws.

The shaft 482 is extended outwardly from the bracket 422, as indicated in Fig. 17, and fixed thereto is an arm 524. Upon movement of this arm upwardly, as viewed in Fig. 18, the inner arms 484, 486 and 498 will all be moved inwardly toward each other to move the associated gripper jaws away from the flange of the counter. Mechanism for moving the arm 524 will be described later. This arm is normally maintained in the position illustrated in Fig. 18 with the inner arms in their outermost positions by means of a leaf spring 526 connected thereto and engaging a pin 528 threaded into the outer wall of a bearing 530 on the outer end of the bracket 422, as shown in Figs. 17 and 18. An adjustable set screw 532 determines the position of the arm 524 when moved by the spring 526 and, accordingly, determines the outermost position of the gripper jaws 502.

In order to move the jaws 518 away from the jaws 502 to permit the release of a counter from the grippers, pins 534 connecting the links 512 to the arms 506, 508 and 510 are extended outwardly, as indicated in Fig. 24 and are arranged to be engaged by a lifting member 536. The lifting member 536 is fixed to a shaft 538 (Fig. 18) 70 slidably mounted in the bracket 422 parallel to the shaft 424. The shaft 538 is normally urged downwardly by means of a spring 540 located between the bracket 422 and the member 536. The opposite end of the shaft 538 carries a pin 75

542 resting on an inclined surface 544 of an arm 546 keyed to the end of a shaft 548. The shaft 548 is rotatably mounted within the bearing 530 and is provided with a handle 550 at the end opposite the arm 546 by means of which the shaft 548 may be rotated. As the shaft 548 is rotated in a clockwise direction, as viewed in Fig. 19, the surface 544 thereof engaging the pin 542 will cause movement of the shaft 538 against the force of the spring 540 whereupon the lifting member 536 will engage the projecting portions of the pins 534 to lift the outer gripper jaws 518 away from the inner gripper jaws 502. The end of the arm 524 remote from the shaft 482 carries an adjustable screw 552 having a rounded outer portion arranged to engage a flat surface 554 arranged on the inner end of the handle 550. As the arm 524 moves the inner gripper jaws 502 inwardly the screw 552 moves toward the flat surface 554 of the handle 550 and after the inner grippers have been moved inwardly an amount which is determined by the setting of the screw 552 this screw will engage the handle 550. Upon further movement of the arm 524, the handle 550 will be moved, causing rotation of the shaft 548 to move the shaft 538 against the force of the spring 540. After the shaft 538 has been moved sufficiently, the member 536 engages the projecting portions of the pins 534 causing movement of the outer gripper jaws supporting arms against the force of the springs 514 to move the outer gripper jaws 518 away from the inner gripper jaws 502. The handle 550 also enables the operator to manually move the gripper jaws 518 away from the gripper jaws 502 when these latter jaws are in their outer positions to facilitate the insertion of a counter with the flange between the sets of gripper jaws.

Fig. 18 illustrates the relative positions of the gripper jaws and associated parts after the flange of the counter has been inserted in the grippers. This figure also illustrates a counter C partially inserted in the upper and a last L carrying an insole I also partially inserted in the upper by mechanism to be described. A pin 560 is slidably mounted in a bearing 562 in the bracket 422 and is arranged to engage the flat surface 564 at the end of the arm 524 whereupon movement of the pin 560 will cause movement of the arm 524 against the force of the spring 526. As shown by the dotted-line position of the pin 560 in Fig. 14, when the counter supporting assembly 420 has been rotated and moved inwardly with respect to the upper, the pin 560 is moved into engagement with the end 562 of a bell crank lever 564 pivoted at 566 to the upper portion of the bearing 426. The other end of the bell crank lever 564 is connected by means of a link 568 to an arm 570 journaled on the shaft 112. As shown in Fig. 3, the arm 570 is connected to the arm 92 operating the tack drivers and the wiper 190 so that the bell crank lever is operated simultaneously therewith. As the counter is being inserted in the upper, the pin 560 engages the end 562 of the bell crank lever 564 which is subsequently moved in a counterclockwise direction, as viewed in Fig. 14, thus causing movement of the pin 560 toward the right which in turn causes movement of the inner gripper jaws inwardly with respect to the flange of the counter. As the inner gripper jaws move inwardly, they exert a wiping action on the lining of the upper which is located between the inner gripper jaws and the last to pull the lining tight about the last. Figs. 20 to 23 illustrate the different posi-

tions assumed by the gripper jaws. As indicated in Fig. 21, as the inner gripper jaws move toward the inner edge of the counter flange, the outer gripper jaws move under the influence of the springs 514 to force the counter inwardly in the upper and maintain the flange of the counter tight against the lining. By reason of the connection of these jaws to the supporting arms by the leaf springs 520, these jaws are permitted to tip as shown in Figs. 21 and 22 so that the entire gripping surfaces thereof are maintained in engagement with the flange of the counter. In Fig. 22 the inner gripper jaws have been moved inwardly to their extreme positions, this movement being permitted by reason of the cutaway portions of the arms 484 and 486, as indicated at 487 (Figs. 18, 20, and 21). The jaws 502 are also shaped, as indicated in Fig. 24, so that they will fit together and lie entirely within the space bounded by the inner margin of the counter flange, as shown in Fig. 25. The member 536 is then lifted to the position shown in Fig. 23 to move the outer gripper jaw supporting arms upwardly. Since the pressure between these outer gripper jaws and the counter is now removed the outer gripper jaw supporting arms move inwardly under the influence of the springs 515 whereupon they assume the positions indicated in Fig. 23. The lower portions of the arms 506 and 508 supporting the outer gripper jaws are also cut away as indicated in Fig. 19 so that they may clear the lower portions of the arms 486 and 484 respectively in moving to the position shown in Fig. 23. The counter grippers may now be moved away from the assembled upper, counter and last.

The last of form supporting and inserting mechanism is illustrated in Figs. 1, 2, 4, and 26 to 30. Arms 600 extend vertically upward at each side of the machine and are supported by means of a shaft 602 mounted in bearings 604 and 606 in the side walls 12 and 14 of the machine. These arms are urged forwardly of the machine by means of springs 608 (Fig. 2) acting between sleeves 610 pivoted to the side walls of the machine and bosses 614 on the upper portions of the arms 600. Rods 612 are received by the bosses 614 in the arms 600 and are pivoted thereto by means of screws 616. The rear ends of the rods 612 pass through the sleeves 610 and are provided with nuts 618 on the rear side of the sleeves to adjustably limit the forward movement of the arms 600.

In the upper ends of the arms 600 are journaled stub shafts 620 and secured to these stub shafts by means of the split bearings 622 (Fig. 26) is the U-shaped supporting member 624 extending rearwardly of the machine. The rear or transverse connecting portion 626 of the member 624 is provided with a slideway to receive the slide member 630 (Figs. 4 and 26). This slide member is substantially U-shaped, as indicated in Fig. 4, with the legs of the U projecting upwardly. The lower forward portion of the slide 630 is provided with teeth 632 (Fig. 26) with which engages a pawl 634 pivoted at 636 to the U-shaped member 624. A spring 638 urges the pawl 634 into engagement with the teeth 632 to maintain the slide 630 in any desired position. Gibs 639 fastened to the rear of the member 624 complete the slideway for the slide 630.

A last supporting member 640 is slidably mounted on the slide 630, the member 640 having portions 642 (Figs. 4 and 27) embracing the legs

of the slide 630. Springs 644 positioned between the slide 630 and the member 640 urge the member 640 upwardly against a pin 646 extending between the legs of the slide 630 adjacent to the upper end thereof. Slidably received by the member 640 is a last pin 650 arranged to be inserted within the thimble in the rear portion of a last. A pair of clamping members 652 is mounted on the member 640 above the last pin 650 and a similar pair of clamping members 654 is mounted on the member 640 below the last pin, these clamps being arranged to engage the cone of a last adjacent to the last pin to centralize the last with respect to the upper. These clamping members are formed, as indicated in Fig. 27, as a pair of bell-crank levers 656, one arm of each lever forming a clamping surface and the other arms of the levers extending toward one another and being interconnected by means of a pin 658 secured to one of the levers and being engaged by a forked portion 660 at the end of the other lever. Springs 662 located between the member 640 and the arms 656 of the clamping members urge the clamping surfaces thereof toward one another. Since the clamping members are interconnected at 658 and 660, movement of either one against the force of the spring 662 will cause an equal and opposite movement of the other clamping member.

The last pin 650 is held in retracted position prior to the insertion of a last between the clamping members and the end of the last pin is notched at 670 to receive the rounded end 672 of a lever 674. This lever is pivoted at 676 to an arm 678 extending rearwardly from the slide 630 and the other end of the lever extends forwardly of the machine in the form of a handle 680. The lever 674 also carries a pawl releasing member 682 arranged to engage an arm 684 integral with the pawl 634 upon movement of the lever in a clockwise direction. A spring-pressed ball 686 carried by the lever cooperates with a pair of recesses 688 and 690 yielding to hold the lever 674 in either of two positions. With the lever in the position illustrated, the last pin 650 has been moved forwardly and is received by the thimble in the last. Upon movement of the lever in a clockwise direction the last pin 650 is moved rearwardly and out of the thimble in the last and at the same time the member 682 carried by the lever engages the arm 684 of the pawl 634 to move the pawl against the force of the spring 638 out of engagement with the teeth 632 of the slide 630. The slide 630 will now move downwardly under the force of gravity, carrying with it the member 640 and the associated clamps and last pin until the lower end of the member 640 engages the U-shaped member 624. In order to move the slide 630 upwardly the operator first rotates the lever 674 by means of the handle 680 to move the last pin 650 forwardly of the machine and to permit engagement of the pawl 634 with the teeth 632 on the slide 630. The last pin is tapered at its outer end to facilitate its insertion in the thimble of the last. If the last is incorrectly positioned lengthwise of the last support, the last pin, upon its movement into the thimble of the last, will exert a cam action to move the last lengthwise to the proper position. The slide is then moved upwardly by exerting an upward force on the handle without causing the same to move about the pivot 676, the pawl 634 preventing downward movement of the slide.

The stub shafts 620 supporting the U-shaped member 624 and the rest of the last supporting assemblage are arranged to pass substantially through the center of curvature of the rear portion of a last which has been inserted between the clamping members 652 and 654 with the last pin 650 received by the thimble of the last when the last has been moved upwardly for insertion in the upper. In order to position the last within the upper the last is rotated about the axis of the shafts 620. For this purpose a roll 700 is pivoted to a projection 702 (Fig. 27) on the supporting member 624. The roll 700 is received by the forked end 704 of a lever 706 fixed to a shaft 710 (Fig. 4) journaled in a bearing 712 in the wall 12 of the machine. An arm 714 also fixed to the shaft 710 extends rearwardly of the machine and carries a cam follower 716 (Figs. 1 and 29). The cam follower 716 is received by a cam groove 718 cut in the inner surface of the driven gear 720 fixed to the driven shaft 126. During one portion of the rotation of the gear 720 the shaft 710 will be rotated in a clockwise direction by the arm 714, thus causing upward movement of the end 704 of the lever 706 and moving the U-shaped supporting member 624 in a counterclockwise direction about the axis of the shafts 620. This movement of the supporting member 624 causes the last supporting member 640 to move in the same manner whereupon the rear portion of a last which has been previously inserted in position, as shown in Fig. 26, will move toward the bottom of the upper and the toe portion of the last will move through the bottom of the upper toward the top of the toe portion thereof. Since the last rocks about an axis which passes substantially through the center of curvature of the rear part thereof, a very effective wiping action takes place on the lining at the rear part of the upper.

When the last is first positioned as shown in Fig. 26, the vertical position thereof is determined by the gripper jaw 54 engaging the inside of the heel portion of the upper at the top thereof. The springs 644 maintaining the last supporting member 640 in its uppermost position will yield to permit sufficient downward movement of the last upon being rotated in the manner previously described to ride over the gripper member 54 and after the last has cleared this gripper the springs 644 will urge the member 640 upwardly so that the last will be in proper engagement with the lining at the heel portion of the upper to exert its wiping action thereon.

The gear 720 meshes with a driving gear 722 which is arranged to be connected to a driving pulley 724 by means of a single revolution clutch. This clutch consists of a driving member 725 (Fig. 3) carried by the pulley and arranged to engage a pin 726 (Fig. 2) slidably connected to the hub of the gear 722. The pin 726 is urged toward the driving member 725 of the pulley by means of a spring 728. Normally maintained in the path of movement of a member 730 connected to the pin 726 is a stop arm 732 pivoted at 734 to the frame of the machine. The upper end of the arm 732 has a cam surface 736 (Fig. 3) against which the member 730 moves during the rotation of the gear, the member 730 being moved toward the left upon engagement with the cam surface to move the pin 726 away from the driving member 725 of the pulley 724. The arm 732 is normally maintained in the position illustrated by means of a spring 738 (Fig. 2) and may be 75

rotated in a clockwise direction upon upward movement of a member 740 yieldably connected to the upper end of a rod 742 pivoted to a treadle 744. Upon depression of the treadle and upward movement of the rod 742 the member 740 moves the stop arm 732 outwardly to release the pin 726 and permit clutching of the gear 722 and the pulley 724. After the stop arm 732 has been moved outwardly a sufficient distance, the yieldingly mounted member 740 will pass by the member 742 allowing it to return to the position illustrated so as to disconnect the pulley and gear after the completion of a single revolution thereof. Upon release of the treadle by the operator 15 the member 740 passes over the shoulder 746 by reason of the yielding mounting of the member 740 and then snaps back to the position illustrated so that upon a subsequent treading operation the gear 722 and the driving pulley will again be connected. The relative sizes of the gears 720 and 722 are such that a single revolution of the gear 722 causes one-third of a revolution of the gear 720.

The sequence of operations of the various parts of the machine will best be understood upon reference to the cam chart of Fig. 31. At the end of a cycle of operations the supporting member 624 (Fig. 26) for the last-supporting assemblage will be in a substantially horizontal position, which position was assumed upon the insertion of the last within the upper. The lining gripper jaws 350 and 354 will be in their forward position as indicated in Fig. 12 to which position they were moved to permit insertion of the last within the upper. The latch-setting arm 132 is in the dotted line position of Fig. 13 to which position it was moved at the end of the cycle to lock the gripper jaws 60 and 154 in their retracted positions. At the beginning of 40 the first part of the cycle of operations the operator treads the machine causing the driven shaft 126 to move through one-third of a revolution, whereupon the cam groove 718 in the gear 720 (Fig. 29) causes the arm 714 to move the shaft 710 in a counterclockwise direction thereby rocking the supporting member 624 downwardly and rearwardly to return the last-supporting member 640 to a position rearwardly of the position assumed by the upper when it is placed in the machine. At this time the handle 680 (Fig. 26) will be in the other position from that shown in which position the last-pin 650 is retracted and the pawl 534 is out of engagement with the teeth 632 on the slide 630 so that this slide is in its lowermost position. During the initial part of the rearward movement of the last-supporting member 640, the cam groove 138 in the cam 140 moves the latch-setting arm 132 back to the full line position of Fig. 13 so that it will be out of the way of the gripper jaws 60 and 154 when they are released for downward movement by the operator. As soon as the last-supporting member 640 has reached its rearmost position, the cam groove 390 (Fig. 12) will cause movement of the lining gripper jaws into the full line position in which position they are ready to receive the lower margin of a lining. After the lining gripper jaws have reached this position the machine stops and is ready to receive an upper.

The operator now places the inside of the top rear margin of an upper U on the gripper jaw 54 (Figs. 6 and 7) with the back seam properly lined up with respect thereto. The handle 72 is now depressed to cause the release of the latch

68, permitting the upper gripper jaw 60 to move into engagement with the upper under the influence of the spring 62 so that the top rear portion of the upper is now firmly held between the gripper jaws 54 and 60. The lasting margin at the heel end of the upper is placed over the gripper jaws 176 (Figs. 8-10), handle 170 is depressed, thus releasing the latch 162 and the gripper jaws 154 move downwardly under the influence of the spring 174 to clamp the lasting margin 10 at the rear part of the upper between the gripper jaws 154 and 176. The heel end of the upper is now held in place at the top and bottom thereof and the proper location thereof with respect to the other parts of the machine is determined by the prior adjustment of the slide 30 carrying gripper jaws 54 and 60 (Fig. 7) with respect to the front of the machine, the shank portion 52 of the gripper jaw 54 forming a gage against which the top rear margin of the upper is placed. 20

With the heel portion of the upper properly secured by the grippers, the lasting margin at the forepart thereof is secured between the gripper jaws 270 and 272 (Figs. 2 and 11), the handle 282 being depressed to permit insertion of the upper between the jaws and then released whereupon the forepart is maintained between the jaws under the force of the spring 288. The handle 368 (Figs. 11 and 12) attached to the jaw 354 is depressed to permit the lower part of the lining D to be inserted between this jaw and the jaw 350. The handle is then released and the spring 366 moves the jaw 354 against the lower part of the lining which is thus held firmly between the jaws 350 and 354. 25

The counter inserting mechanism 420 is at this time in the position indicated in Fig. 2 and is ready for the reception of a counter. The handle 550 (Fig. 17 to 19) will be operated to rotate the shaft 548 which causes movement of the shaft 538 against the force of the spring 540 to move the outer gripper jaws away from the inner gripper jaws whereupon a counter C may be inserted with its flange between the inner and outer gripper jaws and properly aligned with respect to the gripper at the rear part thereof. When the counter has been properly placed therein, handle 550 is released to permit movement of the member 536 away from the pins 534 and the outer gripper jaws move against the flange of the counter under the influence of the springs 514. 40

The operator now treadsles the machine, starting the second part of the cycle of operations. The cam groove 390 in the cam 392 (Fig. 12) causes movement of the lining gripper to the intermediate position indicated by the broken lines in Fig. 12 and this movement carries the lining inwardly and away from the upper. Since the lining gripper moves about an axis which passes through the upper at a point substantially coincident with the line of stitching of the lining at the rear part of the upper, the lining will be maintained under substantially the same tension as when it was placed between the lining gripper jaws so that it will not wrinkle or become stretched. When the driving shaft 126 has rotated 165° from the initial position the lining gripper will be in the intermediate position of Fig. 12. Simultaneously with the moving of the lining gripper at the beginning of the second part of the cycle the cam groove 442 in the cam 124 (Figs. 14 and 16) moves the shaft 434 axially to turn the shaft 424 carrying the counter supporting assembly 420 from the vertical position illus- 50

trated in Fig. 2 to a position in which the counter is somewhat below the rear part of the upper but in alignment therewith. This turning movement of the shaft 424 terminates at the same time that the lining grippers reach their retracted position or after the driven shaft 126 has rotated through 165° as indicated by the cam chart. The cam 124 through the cam groove 444 also starts moving the shaft 424 carrying the counter gripper assembly inwardly to move the counter toward the upper which has been placed in the machine, this inward movement of the counter assembly also starting at the beginning of the second part of the cycle. As will be noted by the cam chart, the forward movement of the counter assembly is not completed at the time that the lining gripper assembly is in its retracted position. 55

After the shaft 126 has moved through 165° the lining gripper starts to move back to the full line position of Figs. 11 and 12 and reaches this position after 210° of rotation of the shaft 126. Coincident with the movement of the lining gripper to return the lining to the original position, the cam groove 442 of the cam 124 moves the shaft 424 in a direction opposite to that in which it was previously moved to move the counter upwardly so that it will be in proper engagement with the heel portion of the upper during the last part of the inward movement of the counter. The upper and inward movements of the counter terminate at the same time that the return movement of the lining grippers terminates or at 210° of rotation of the shaft 126. The cam groove 408 in the cam 392 (Fig. 30) operates the lever 404 to cause the member 396 to move to the dotted line position of Fig. 30 during the return movement of the lining grippers and causes the release of the lower jaw of the lining grippers just after the lining grippers have returned the lining to the original position. During the last part of the second portion of the cycle of the machine the member 396 moves back toward the position shown in Fig. 30 and the lining grippers 45 move to the outermost position illustrated in Fig. 12 whereupon the machine again stops. The counter is now properly inserted between the lining and the upper and if the counter has been properly placed in the counter grippers and the upper has been properly placed in the upper grippers the proper alignment of the rear part of the counter and the back seam of the upper is insured. 50

The upper with the inserted counter is now ready for the reception of the last. The operator passes a last L through the bottom of the upper and places it on the last support 640 between the clamping members 652 and 654 as shown in Fig. 26. These clamping members insure the proper centralization of the last with respect to the assembled upper and counter. The last pin 658 is now inserted in the thimble of the last by moving the handle 680 about its fulcrum to the position illustrated in Fig. 26. This movement of the handle 680 also permits movement of the pawl 634 under the influence of the spring 638 into engagement with the teeth 632 on the slide 630. The slide 630 is now moved upwardly by exerting upward pressure on the handle 680 until the rear part of the last engages the gripper jaw 54 which acts as a gage to insure the proper positioning of the last as shown in Fig. 26. The last is now ready to be moved into position in the upper by the machine. 65

The operator now treadsles the machine, thus

initiating the third part of the cycle of operation. At this time, the cam groove 408 of the cam 392 completes the movement of the member 396 (Fig. 30) back to the full line position. The cam groove 718 in the driven gear 720 (Fig. 29) causes clockwise movement of the arm 706 which in turn causes the supporting member 624 of the last inserting mechanism to move in a counterclockwise direction about the axis of the shafts 620 (Fig. 26). The last is accordingly moved into proper position in the upper. At the beginning of the movement of the last, the last support 640 will be moved downwardly by the engagement of the last with the gripper jaw 54 against the force of the spring 644 thereby permitting the heel end of the last to ride over the gripper jaw 54. After the rear end of the last has cleared this gripper jaw, the spring 644 will move the rear end of the last into proper engagement with the rear end of the upper.

Simultaneously with this movement of the last, the cam groove 332 in the cam 140 (Fig. 13) operates to move the forepart gripper downwardly by imparting a counterclockwise rotation to the shaft 310 to tension the upper lengthwise. The connection between the cam and the shaft 310 is a yielding and adjustable one by reason of the spring 332 and nuts 320 so that the degree of lengthwise tension imparted to the upper is yielding and variable. Since the upper is under lengthwise tension during the movement of the last therein, an effective wiping action is imparted to the lining by the movement of the rear part of the last both at the sides and rear part of the heel portion of the upper.

Before the last has been completely inserted in the upper, the cam groove 122 of the cam 124 (Fig. 14) starts rotating the bell crank lever 564 in a counterclockwise direction to move the pin 560 carried by the supporting bracket 422 for the counter supporting assembly 420 forwardly of the machine. This movement is imparted to the arm 524 to move this arm against the force of the spring 526 which causes movement of the inner counter gripper jaws 502 inwardly from the position indicated in Fig. 18. At the time that these grippers begin to move inwardly the last will have been moved into the upper to the position shown in Fig. 18. During the last part of the movement of the last, the inner gripper jaws 502 move inwardly to the position shown in Fig. 20. This inward movement of the counter grippers imparts a wiping action to the lining to pull it tightly about the last as shown in Fig. 20. The movement of the last stops when the inner counter gripper jaws reach the position of Fig. 20 but these counter gripper jaws continue to move inwardly as indicated in Figs. 21 to 23. As indicated in Fig. 20 the presence of the inner gripper jaws between the lining D and the flange of the counter C has prevented complete insertion of the counter within the upper. The outer counter gripper jaws 518 exert a force tending to move the counter inwardly by reason of the springs 514 so that as the inner gripper jaws move inwardly, the outer gripper jaws force the counter into the upper with the flange thereof holding the margin of the lining against the insole which has previously been attached to the last as indicated in Fig. 22. When the inner gripper jaws have moved entirely out of engagement with the counter flange, the rounded head of the screw 552 carried by the arm 524 (Fig. 18) engages the flat surface 554 of the handle 550 to 75

rotate the shaft 548. This causes movement of the shaft 538 carrying the lifting member 536 against the force of the spring 540 to lift the outer counter gripper jaws 518 away from the counter flange, whereupon the springs 515 cause the outer gripper jaws and their supporting arms to move to the positions shown in Fig. 23.

Simultaneously with the movement of the counter grippers away from the counter flange, the arm 92 (Figs. 7, 9, and 14) is moved by the cam groove 122 in the cam 124 in a direction to operate the tack drivers 84 and 220. At the same time, the wiper 190 of Fig. 9 moves downwardly over the heel end of the upper to wipe the margin thereof over the rear end of an insole on the last. Tension is imparted to the upper over the heel end at the same time by the downward movement of the gripper jaws 154 and 176. By the time that the counter grippers have moved to the position of Fig. 23 the tack driver 84 (Figs. 6 and 7) drives a tack through the heel portion of the upper into the heel portion of the last adjacent to the back seam near the top of the upper. At this time, the gripper jaws 154 and 176 will have pulled the upper over the heel end of the last and the wiper 190 will have wiped the margin thereof against the heel portion and when the tack driver 84 drives a tack into the back of the last, the latch 242 (Fig. 9) is released, whereupon the spring 234 operates the tack driver 220 to drive a tack through the margin of the upper, the flange of the counter C, the lining D and the innersole I attached to the last L at the heel end thereof. The movement of the tack driver 220 causes movement of the positioning device 210 to position the tack supported thereon in the passageway 208 in alignment with the tack driver 220.

The upper is now secured to the innersole by a tack in the bottom through the counter flange and the lining and to the last by a tack adjacent to the top margin near the back seam. At the completion of the tacking and wiping operation, the counter inserting mechanism begins to move away from the upper forwardly of the machine and shortly after it starts to move forwardly of the machine it will begin to rotate about the axis of the shaft 424 back to the vertical position where it will be out of alignment with the upper and ready to receive another counter. Simultaneously with this movement the counter grippers will be moved back to the position shown in Fig. 18 by the force exerted by the spring 526 on the arm 524. The gripper jaws 60 and 154 are moved upwardly away from the gripper jaws 54 and 176 respectively at the completion of the tacking and wiping operation by reason of the clockwise movement of the lever 132 (Fig. 13), the portions 134 and 260 thereof engaging the members carrying the gripper jaws 60 and 154 respectively. These gripper jaws are moved upwardly with respect to the gripper jaws 54 and 176 back to the positions illustrated in Figs. 7 and 9 wherein they are held by the latches 66 and 162 respectively.

At the same time, the wiper 190 (Fig. 9) and the associated grippers are moved as a unit back to the position illustrated until the shoulder 262 of the tack driving lever 222 engages the bar 264, thus turning the lever 222 in a clockwise direction until the latch 242 moves into locking engagement with the member 240 thus locking the tack driver 220 in retracted position, this movement of the tack driver moving the positioning device 210 into position to receive a tack

delivered through the vertical passageway 202. During this time, the lengthwise tension of the upper is relieved by movement of the lever 324 (Fig. 13), back to the position illustrated, by the groove 832 of the cam 140.

The machine has now completed its cycle of operation and stops with the counter inserting assembly in position to receive another counter, with the outer rear part gripper jaws in retracted positions and the tack drivers also in retracted positions. The operator now moves the handle 202 (Fig. 4) downwardly to move the gripper jaw 272 away from the gripper jaw 270 and he also moves the handle 680 upwardly to withdraw the last pin 650 from the last. This movement of the handle 680 also causes movement of the pawl 638 away from the teeth 632 on the slide 630 whereupon the slide moves down under the influence of gravity carrying with it the last supporting member 640 and the last and upper which is still held thereon by means of clamps 652 and 654. The assembled upper counter and last may now be removed from the machine by the operator by withdrawing the last from the clamping members 652 and 654 and the machine is now in readiness to start a new cycle of operation to assemble another upper, counter and last.

Having described my invention, what I claim is new and desire to secure by Letters Patent of the United States is:

1. In an assembling machine, means for supporting an upper for the reception of a counter, means for supporting a counter, and means for relatively moving said supporting means to position the counter within the upper.

2. In an assembling machine, means for supporting an upper for the reception of a counter, and means for moving a counter into the upper.

3. In an assembling machine, means for supporting an upper in vertical position, and means for moving a counter into the upper.

4. In an assembling machine, means for supporting an upper for the reception of a counter, means for supporting a counter in a position out of alignment with the upper to facilitate the positioning of the upper in the upper-supporting means, and means for swinging the counter-supporting means into alignment with the upper and moving the counter-supporting means toward the upper to insert the counter therein.

5. In an assembling machine, means for supporting an upper for the reception of a counter, and means for moving a counter into the upper, said means imparting to the counter a component of movement rearwardly of the upper to position properly the counter in the rear part of the upper.

6. In an assembling machine, means for supporting an upper for the reception of a counter, means for supporting a counter in a position outwardly and rearwardly of the upper to facilitate the positioning of the upper in the upper-supporting means, means for moving the counter-supporting means inwardly toward the upper, and means for simultaneously moving the counter-supporting means into a position forward of the rear part of the upper and then moving the counter-supporting means back toward the rear part of the upper.

7. In an assembling machine, means for supporting an upper for the reception of a counter, means for supporting a counter, means for relatively moving said supporting means to position the counter within the upper, and means asso-

ciated with the upper-supporting means for gaging the heightwise position of the upper with respect to the inserted counter.

8. In an assembling machine, means for supporting an upper for the reception of a counter, said supporting means comprising grippers engaging the rear part of the upper at the top margin and at the last margin thereof with the forepart of the upper hanging downwardly therefrom, means for supporting a counter, and means for moving said counter-supporting means to position the counter within the upper.

9. In an assembling machine, means for supporting an upper for the reception of a counter, said supporting means comprising grippers engaging the rear part of the upper at the top margin thereof and at the last margin thereof, means for supporting a counter, means for moving said counter-supporting means a predetermined distance toward the upper to position the counter within the upper, and means associated with the top margin gripper for gaging the heightwise position of the upper with respect to the inserted counter.

10. In an assembling machine, means for supporting an upper, means for supporting and inserting a counter in said upper, said counter-supporting and inserting means comprising grippers engaging the flange of a counter, an arm supporting said grippers, a rotatable shaft supporting said arm, said shaft being movable axially toward and away from said upper, and means for simultaneously rotating and axially moving said shaft to move the counter into the heel end of said upper.

11. In an assembling machine, means for supporting an upper, means for supporting and inserting a counter in said upper, said counter-supporting and inserting means comprising grippers engaging the flange of a counter, an arm supporting said grippers, a rotatable shaft supporting said arm, said shaft being movable axially toward and away from said upper, means for simultaneously rotating and axially moving said shaft to move the counter into the heel end of said upper, and means actuated after the insertion of the counter in the upper for opening said grippers and moving them inwardly with respect to the flange of the counter.

12. In an assembling machine, means for supporting a lined upper for the reception of a counter, means for moving the lining away from the rear part of the upper, and means for moving a counter between the lining and the upper while the lining is held spaced from the upper.

13. In an assembling machine, means for supporting a lined upper for the reception of a counter, means for gripping the lower margin of the lining in the rear part of the upper and moving the lining to space it from the upper, means for moving a counter into the upper, and means for operating said lining gripping means to move the lining into engagement with the inner surface of the inserted counter.

14. In an assembling machine, means for supporting a lined upper for the reception of a counter, means for moving the lining at the rear part of the upper to space it from the upper, said means being arranged to maintain the lining free from wrinkles during its movement, means for inserting a counter within the upper, and means for operating said lining moving means to move the lining into engagement with the upper while maintaining the lining free from wrinkles.

15. In an assembling machine, means for supporting a lined upper for the reception of a counter, means for gripping the lower margin of the lining at the rear part of the upper and moving the lining away from the rear part of the upper and then moving the lining into engagement with the inner surface of an inserted counter, and means for subsequently releasing the lining grippers and moving them outwardly with respect to the upper.

16. In an assembling machine, means for supporting a lined upper for the reception of a counter, gripping means for engaging the lasting margin of the lining at the rear part of the upper, means for supporting a counter outwardly with respect to the upper, means for moving the counter-supporting means to move the counter into the upper, and means for simultaneously swinging said lining gripping means to move the lining away from the upper at the rear part thereof during the first part of the counter movement and moving the lining back toward the rear part of the upper during the latter part of the counter movement.

17. In an assembling machine, means for supporting an upper having an attached lining, gripping means for engaging the lasting margin of the lining at the rear part of the upper, and means for swinging said gripping means to move the lining away from the rear part of the upper to facilitate the insertion of a counter therebetween.

18. In an assembling machine, means for supporting an upper having an attached lining, gripping means for engaging the lasting margin of the lining at the rear part thereof, means for swinging said gripping means to move said lining away from the rear part of said upper and then swinging the gripping means back to its original position, and means actuated after movement of the gripping means back to its original position to cause release of the gripping means from the lining.

19. In an assembling machine, means for supporting an upper having an attached lining, gripping means for engaging the lasting margin of the lining at the rear part thereof, means for swinging said gripping means to move said lining away from the rear part of said upper and then swinging the gripping means back to its original position, means actuated after movement of the gripping means back to its original position to cause release of the gripping means from the lining, and means for then moving the gripping means away from the upper to permit the insertion of a last therein.

20. In an assembling machine, means for supporting an upper having an attached lining, gripping means for engaging the lasting margin of the lining adjacent the rear part thereof, and means for swinging said gripping means to move the lining away from the rear part of the upper to facilitate the insertion of a counter therebetween and then swinging the gripping means back to the initial position, said gripping means being swingable about an axis passing substantially through the point at which the lining is stitched to the rear part of the upper so that the lining is maintained under a substantially constant degree of tension during the swinging movements of the gripping means.

21. In an assembling machine, means for supporting an upper having an attached lining, gripping means for engaging the rear part of the lining at the lasting allowance, said gripping

means being mounted on an arm pivoted on an axis passing substantially through the point of stitching through the lining and the rear part of the upper, and means for swinging said arm to move said lining away from the upper and subsequently moving said lining back adjacent to the rear part of the upper.

22. In an assembling machine, means for supporting an upper having an attached lining, gripping means for engaging the rear part of the lining at the lasting margin, said gripping means comprising a pair of cooperating jaws, one of said jaws being spring pressed toward the other, an arm supporting said gripping means, said arm being pivoted about an axis passing substantially through the point at which the lining is stitched to the rear part of the upper, means for swinging said arm to move the lining away from the upper to facilitate the insertion of a counter therein and then swinging the arm in the reverse direction to replace the lining within the upper, and means engaging one of said jaws at the termination of the reverse movement of said arm to move said jaw away from the other jaw to release the lining, said swinging means then moving said arm to swing said gripping means away from the upper.

23. In a machine for operating on shoe parts, means for supporting a counter, said means comprising a plurality of grippers having cooperating jaws for engaging opposite sides of the flange of a counter, and means for moving said jaws of each gripper relatively to one another to enable insertion and removal of a counter in and from the grippers.

24. In a machine for operating on shoe parts, means for supporting a counter, said means comprising a plurality of grippers, each of said grippers having cooperating jaws arranged to engage opposite sides of the flange of a counter, supporting arms for said jaws, and leaf springs connecting the jaws arranged to engage the outside of the counter flange to the respective supporting arms whereby the jaws may move relative to the supporting arms but are normally maintained in predetermined positions with respect thereto.

25. In a machine for operating on shoe parts, means for supporting a counter, said means comprising a plurality of grippers having cooperating jaws for engaging opposite sides of the flange of a counter, movable supporting arms for supporting said jaws, means connecting the jaws engaging the inner side of the counter flange for limited pivotal movement on the respective supporting arms, and leaf springs connecting the jaws engaging the outer side of the counter flange to the respective supporting arms, thereby permitting movement of the jaws with respect thereto while normally maintaining the jaws in predetermined positions relatively thereto.

26. In a machine for operating on shoe parts, means for supporting a counter, said means comprising a plurality of grippers, each of said grippers comprising cooperating jaws arranged to engage opposite sides of the flange portion of a counter, means for causing relative movement between the jaws of each gripper, and means for maintaining the jaws of each gripper adjacent to one another.

27. In a machine for operating on shoe parts, means for supporting a counter, said means comprising a plurality of grippers, each of said grippers having cooperating jaws arranged to engage opposite sides of the flange of a counter,

means urging the jaws of each gripper toward one another, means for moving the jaws engaging the inner side of the flange inwardly toward one another and away from the flange, and means for subsequently moving the other jaws of each gripper away from the other side of the flange of the counter.

28. In an assembling machine, means for supporting a lined upper, means for supporting a flanged counter to be inserted within said upper, said counter-supporting means comprising a plurality of grippers having cooperating jaws for engaging the flange of the counter on opposite sides thereof, means for moving the jaws engaging the inner side of the flange inwardly with respect thereto following the insertion of a last within the upper, and means for causing the jaws engaging the outer side of the flange to exert a pressure thereon until the first-mentioned jaws have moved entirely out of engagement with the flange.

29. In an assembling machine, means for supporting a lined upper, means for supporting and inserting a flanged counter within said upper, said last-named means comprising a plurality of grippers having cooperating jaws engaging opposite sides of the flange of the counter, means for moving the jaws engaging the inner side of the flange inwardly with respect thereto following insertion of a last within the upper, said jaws being arranged to exert a wiping action upon the lining during the inward movement thereof, and means for causing the jaws engaging the outer portion of the flange of the counter to exert a force to press the counter toward the last while the first-mentioned jaws are moving inwardly with respect thereto.

30. In an assembling machine, means for supporting a lined upper, means for supporting and inserting a flanged counter within said upper, said last-named means comprising a plurality of grippers having cooperating jaws engaging opposite sides of the flange of the counter, means for moving the jaws engaging the inner side of the flange inwardly with respect thereto following insertion of a last within the upper, said jaws being arranged to exert a wiping action upon the lining during the inward movement thereof, means for causing the jaws engaging the outer portion of the flange of the counter to exert a force to press the counter toward the last while the first-mentioned jaws are moving inwardly with respect thereto, and means for thereafter moving said last-named jaws away from said counter.

31. In an assembling machine, means for supporting a lined upper for the reception of a counter, counter-supporting means, means for moving said counter-supporting means to insert a counter between the lining and the upper, and means for moving the counter-supporting means away from the counter following the insertion of a last within the upper, said counter-supporting means being arranged upon movement thereof away from the counter to exert a wiping action upon the lining.

32. In an assembling machine, means for supporting an upper, means for supporting a counter, means for relatively moving said upper and counter-supporting means to insert a counter within the upper, and means for moving a form into the upper following the insertion of a counter therein.

33. In an assembling machine, means for supporting an upper, means for supporting a coun-

ter, means for relatively moving said upper and counter-supporting means to insert a counter within the upper, means for moving a form into the upper, and means for simultaneously exerting a lengthwise tension on the upper.

34. In an assembling machine, means for supporting an upper, means for supporting a counter, means for relatively moving said upper and counter-supporting means to insert a counter within the upper, means for moving a form into the upper, means for simultaneously exerting a lengthwise tension on the upper, said tensioning means comprising a gripper arranged to engage the toe end of the upper, and means mounting said toe gripper for lateral movement with respect to the upper to accommodate an upper for either a right or a left shoe.

35. In an assembling machine, means for supporting an assembled lined upper and counter, means for supporting a form to be inserted in the upper in a predetermined position with the forepart thereof extending outwardly of the forepart of the supported upper, and means for operating said form supporting means to move the form with a rocking motion into the upper to exert a wiping action upon the lining.

36. In an assembling machine, means for supporting an assembled lined upper and counter, means for supporting a form to be inserted therein in a predetermined position with the forepart thereof extending outwardly of the forepart of the upper, means for operating said form-supporting means to move the form with a rocking motion into the upper to wipe the lining therein, and means for simultaneously imparting a lengthwise tension to the upper to increase the wiping action of said form.

37. In an assembling machine, means for supporting an upper, means for inserting a counter in the upper, means for supporting a last in a predetermined position with respect to said supported upper, and means for moving said last-supporting means to move the last into the upper.

38. In an assembling machine, means for supporting an upper, means for supporting a last to be inserted into the upper, means associated with said upper-supporting means acting as a gage for the heel end of said last to determine the position of said last on said last-supporting means, and means for imparting a rocking action to said last-supporting means to move said last into said upper.

39. In an assembling machine, means for supporting an upper, means for supporting a last to be inserted therein, means associated with said last-supporting means for maintaining said last centralized with respect to said upper, means associated with said upper-supporting means acting as a gage for the heel end of the last to determine the position of said last on said last-supporting means with respect to said upper, and means for rocking said last-supporting means to move said last into the upper.

40. In an assembling machine, means for supporting an upper, means for supporting a last to be inserted in the upper, means associated with said upper-supporting means acting as a gage for the heel end of said last to determine the position of said last on said last-supporting means, means for rocking said last-supporting means to move said last into the upper, said last-supporting means including a yieldable member permitting movement of said last with respect thereto as the last is moved into the upper.

41. In an assembling machine, means for supporting an upper in a vertical position with the forepart thereof extending downwardly, said supporting means including a gripper engaging the upper margin of the upper at the heel end, means for supporting a last to be inserted in the upper, said gripper acting as a gage for the vertical height of said last on said last support prior to the insertion of the last within the upper, and means for moving said last-supporting means to move said last into the upper.
42. In an assembling machine, means for supporting an upper, means for inserting a counter within the upper, means for supporting a last, and means for moving said last-supporting means to move the last into the upper, said upper-supporting means including means for gaging the position of said upper on the upper-supporting means and for gaging the position of said last on said last-supporting means.
43. In an assembling machine, means for supporting an upper, means for inserting a counter within the upper, means for supporting a last, means for moving said last-supporting means to move the last into the upper, said upper-supporting means including means for gaging the position of said upper on the upper-supporting means and for gaging the position of said last on said last-supporting means, and means associated with said last support to maintain said last centralized with respect to said upper.
44. In an assembling machine, means for supporting a lined upper, means for inserting a counter between the lining and the upper, means for inserting a last into the upper following the insertion of the counter therein, and means for moving said counter-inserting means away from said assembled upper after the last has been inserted therein, said counter-inserting means being arranged to exert a wiping action on the lining of the upper during the movement thereof away from the assembled upper.
45. In an assembling machine, means for supporting an upper in a substantially vertical position, last-supporting means positioned adjacent to the top portion of the upper and arranged to initially support a last with the forepart thereof extending through the bottom of the upper and the heel end thereof extending through the top of the upper, and means for rocking said last support to move the last into proper position within the upper for the lasting operation.
46. In an assembling machine, means for supporting an upper in a substantially vertical position, last-supporting means positioned adjacent to the top portion of the upper and arranged to initially support a last with the forepart thereof extending through the bottom of the upper and the heel end thereof extending through the top of the upper, means for rocking said last support to move the last into proper position within the upper for the lasting operation, and means associated with said last support for maintaining said last centralized with respect to said upper.
47. In an assembling machine, means for supporting an upper in a substantially vertical position, last-supporting means positioned adjacent to the top portion of the upper when so supported and arranged to initially support a last with the forepart thereof extending through the bottom of the upper and the heel end thereof extending through the top of the upper, means for rocking said last support to move the last into proper position within the upper for the lasting operation, and means for mounting said last support for vertical adjustment to insure proper engagement of the heel end of the last with the heel end of the upper during the insertion thereof.
48. In an assembling machine, means for supporting an upper, mechanism for supporting and inserting a last in said upper, said mechanism comprising a last-engaging means, an arm supporting said last-engaging means for adjustment lengthwise with respect to said upper, and means for turning said arm about an axis extending substantially through the center of curvature of the rear part of the last supported by the mechanism when the last-supporting means has been adjusted to move the heel end of the last into substantial alinement with the heel end of the upper.
49. In an assembling machine, means for supporting an upper, mechanism for supporting and inserting a last in the upper, said mechanism comprising last-engaging means arranged to maintain the last in a centralized position with respect to the upper, an arm supporting said last-engaging means for slidable adjustment lengthwise of said upper, and means for pivoting said arm to move the last into said upper with a rocking motion.
50. In a machine for operating upon shoe parts, means for supporting a last, said means comprising cooperating clamping members for engaging the last at opposite sides of the cone thereof, a movable last pin associated with said clamping members, and means for moving said last pin into the thimble of the last after said last has been engaged by said clamping members.
51. In a machine for operating upon shoe parts, means for supporting a last, said means comprising cooperating clamping members for engaging the last at opposite sides of the cone thereof, means interconnecting said clamping members for equal and opposite movements, a movable last pin associated with said clamping members, and means for moving said last pin into the thimble of the last after said last has been engaged by said clamping members.
52. In a machine for operating on shoe parts, means for supporting a last, said means comprising cooperating clamping members for engaging the last at opposite sides of the cone, means for urging said clamping members toward one another, means interconnecting said clamping members whereby movement of one of said members will cause an equal movement of the other member in the opposite direction, a movable last pin associated with said clamping members, said last pin having a tapered end portion arranged upon movement thereof into the thimble of the last to cause the proper lengthwise positioning of the last on the supporting means, and means for moving said pin into said thimble after said last has been engaged by said clamping members.
53. In an assembling machine, means for supporting an upper for the reception of a last, means for supporting and moving a last into the upper, said supporting means comprising instrumentalities for ensuring the correct positioning of the last with respect to the supported upper, said instrumentalities comprising cooperating clamping members for engaging opposite sides of the cone of the last, said clamping members being urged toward one another and being interconnected for equal movements in opposite directions to ensure the correct centralization of the last with respect to said upper, a movable last pin associated with said clamping members, means for moving said last pin into the thimble of the last after the last has been engaged by said clamping mem-

bers, and means for moving said supporting means to move the last into the upper.

54. In an assembling machine, means for supporting an upper, mechanism for inserting a last in said upper, said mechanism comprising means for supporting a last prior to insertion thereof with the last centralized with respect to said upper, and means for rockling said last-engaging means to move the heel end of the last with a wiping action into the heel end of the upper.

55. In an assembling machine, means for supporting an assembled lined upper and counter in a vertical position, means for supporting a last having an attached innersole with the heel and forepart of the last out of engagement with the upper, means for moving the supporting means to move the last into the upper to a predetermined position, means for wiping the lasting margin of the upper over the heel end of the last, and means for driving a tack horizontally through the heel seat of the upper, the flange of the counter, the lining and the innersole.

56. In an assembling machine, means for supporting an assembled lined upper, and counter in a vertical position, means for moving a last into the upper, and means for driving a tack vertically through the heel end of the upper adjacent to the top margin thereof, through the counter, lining and into the last for securing said upper and counter to the last.

57. In an assembling machine, means for supporting an assembled lined upper and counter in a vertical position, means for moving a last into the upper to a predetermined position, and means for driving a tack vertically through the heel end of the upper adjacent to the top margin thereof, through the counter, lining and into the last for securing the parts in assembled relation.

58. In an assembling machine, means for supporting an assembled lined upper and counter in a vertical position, means for moving a last into the upper to a predetermined position therein, means associated with said last moving means for centralizing said last with respect to said upper, and means for driving a tack vertically through the heel end of the upper adjacent the top margin thereof, the counter, the lining and into the last.

59. In an assembling machine, means for supporting an assembled lined upper and counter in a vertical position, means for moving a last having an attached innersole into the upper to a predetermined position, means for wiping the lasting margin of the upper over the heel end of the last, means for driving a tack horizontally through the heel seat of the upper, the flange of the counter, the lining and the innersole, and means for driving a tack vertically through the heel end of the upper adjacent to the top margin thereof, the counter, the lining and into the last to hold the parts in assembled relationship.

60. In an assembling machine, means for supporting an assembled lined upper and counter in vertical position, means for moving a last having an attached innersole into the upper, means for wiping the heel end of the upper over the last, and means for driving a tack horizontally through the upper, the flange of the counter, the lining and the innersole, means for delivering tacks through a vertical passageway to said tack-driving means, and means controlled by the movement of said tack-driving means for positioning the tack delivered thereto in a substantially horizontal plane.

61. In a machine for operating on shoe parts, a tack driver, means for moving said tack driver in a substantially horizontal plane, a vertical passageway through which tacks are delivered with their points down to said tack driver, and means operated by said tack driver for moving a tack from a position in which its point extends downwardly into a horizontal plane in alignment with said tack driver.

62. In a machine for operating on shoe parts, a tack driver, means for moving said tack driver in a substantially horizontal plane, a vertical passageway through which tacks are delivered to said tack driver, a normally inclined support at the delivery end of said vertical passageway for supporting a tack delivered thereto in a downwardly inclined direction, and means operated by said tack driver for moving said support into a horizontal plane with the tack supported thereby in alignment with said tack driver.

JOHN T. LANCASTER.
